CLAIM

We claim the ornamental design for a seating unit, as shown and described.

DESCRIPTION

FIG. 1 is a perspective view of a first embodiment of a seating unit embodying the present invention;

FIG. 2 is a right side view of FIG. 1, the left side view being a mirror image of the right side;

FIG. 3 is a front view of FIG. 1;

FIG. 4 is a rear view of FIG. 1; and

FIG. 5 is a top view of FIG. 1.

FIG. 6 is a perspective view of a second embodiment of the seating unit embodying the present invention;

FIG. 7 is a right side view of FIG. 6, the left side being a mirror image of the right side;

FIG. 8 is a front view of FIG. 6;

FIG. 9 is a rear view of FIG. 6; and,

FIG. 10 is a top view of FIG. 6.
